UNITED STATES PATENT OFFICE

105,191

DESIGN FOR A HAIR BARRETTE OR SIMILAR ARTICLE

Charles Adler, New York, N. Y.

Application June 9, 1937, Serial No. 69,743

Term of patent 3½ years

To all whom it may concern:

Be it known that I, Charles Adler, a citizen of the United States of America, residing in Manhattan, county of New York, and State of New York, have invented a new, original, and ornamental Design for a Hair Barrette or Similar Article, of which the following is a specification, reference being had to the accompanying drawing, forming part thereof, wherein,

I claim:

The ornamental design for a hair barrette or similar article substantially as shown.

CHARLES ADLER.
